UNITED STATES PATENT OFFICE.

JOHN B. HADAWAY, OF BROCKTON, MASSACHUSETTS, ASSIGNOR TO UNITED SHOE MACHINERY COMPANY, OF PATERSON, NEW JERSEY, A CORPORATION OF NEW JERSEY.

VAMP-TRIMMING MACHINE.

No. 922,627.

Specification of Letters Patent.

Patented May 25, 1909.

Application filed June 17, 1907. Serial No. 379,358.

To all whom it may concern:

Be it known that I, JOHN B. HADAWAY, citizen of the United States, residing at Brockton, in the county of Plymouth and State of Massachusetts, have invented certain new and useful Improvements in Vamp-Trimming Machines; and I do hereby declare the following to be a full, clear, and exact description of the invention, such as will enable others skilled in the art to which it app pertains to make and use the same.

In the manufacture of shoes and particularly of welted shoes it is customary to trim off the projecting edges of the vamp and lining after the shoe has been lasted so that the instrumentalities of the inseam sewing machine and particularly of the looper may not be interfered with during the subsequent operation of sewing the upper and welt to the insole. Heretofore this trimming operation has usually been performed by hand, and the object of the present invention is to provide a machine by which the projecting edges of the vamp and lining can be quickly trimmed off in the desired manner without liability of injury to the shoe.

The several features of the present invention relate to means for causing the vamp and lining to be properly presented to the trimming knife or knives so as to be trimmed in a satisfactory manner at all portions of the shoe, to the construction and arrangement of the vamp trimming knives whereby they are enabled readily to sever the vamp and lining, to means for preventing the cutting edges of the vamp trimming knives from coming in contact with the lasting tacks, and to the relative arrangement of the vamp trimming knives and the means for presenting the vamp and lining to the knives whereby the shoe being operated upon can be readily manipulated to present the desired portions of the shoe to the knives.

In the machine hereinafter specifically described as embodying the various features of the present invention a roll is provided arranged to extend inside of the vamp and lining of a lasted shoe and to raise the vamp and lining away from the insole and direct them between the cutting edges of the trimming knives. This roll is rotated so that the surface in contact with the lining moves in the direction of feed and the roll is provided upon its peripheral surface with spiral ribs or corrugations so that it exerts an outward

wiping action which stretches the lining transversely to the direction of feed. This outward wiping action which is exerted upon the lining constitutes a feature of the present invention which broadly considered is not limited to a construction comprising a spiral ribbed roll but which may be embodied in any suitable means adapted to stretch the lining transversely to the direction of feed.

The machine hereinafter described is provided with a vamp trimming knife and with a coöperating knife arranged to extend inside of the vamp and lining of the shoe. To bring the trimming knives and the guiding roll into as small a space as possible so as to enable narrow toed shoes to be operated upon and also to permit the shoe to be swung without interfering with the operating of the knives, the guiding roll is so arranged that the trimming knife works across the upper end of the roll, that is, the end of the roll remote from the sole of the shoe. This arrangement of the roll and trimming knife is considered to constitute a feature of the present invention which is not limited to a construction in which the roll necessarily acts to stretch the lining transversely to the direction of feed. In accordance with this feature of the invention the coöperating knife may be of any suitable construction and may be separate from or attached to the roll. To secure as simple and compact a construction as possible, however, the coöperating knife is preferably formed integral with the roll, the upper end of the roll being ground off so that the roll presents a cutting edge at the upper end of its peripheral surface. The trimming knife may be of any suitable construction but preferably is a vibrating knife as it has been found in actual practice that a vibrating knife is best adapted to operate on the vamp and lining of a shoe. To permit the vibrating knife to operate without liability of engaging the lasting tacks which project from the shoe upper it is preferably mounted to move about an axis extending substantially parallel to the line of feed and located in a plane above the plane of the sole of the shoe which is being operated upon. By arranging the vibrating knife to move in this manner its cutting edge moves in a path substantially parallel to the plane of the insole while severing the vamp and lining, and during the retracting stroke of the knife its cutting edge is raised above

the sole so as to pass above the ends of the lasting tacks.

The guide roll above referred to acts to raise the vamp and lining from the insole. At certain portions of the shoe, however, and particularly near the toe, the vamp and lining project outwardly, and it is necessary at such points that the vamp and lining be bent inwardly toward the medial line of the shoe in order that they may pass between the cutting edges of the knives. To secure this result a feature of the present invention contemplates the provision of means for bending the vamp inwardly toward the medial line of the shoe. Broadly considered this feature of the invention contemplates the use of any suitable means for accomplishing this result. Preferably, however, a vibrating vamp bending device is provided which acts at each reciprocation of the vibrating trimming knife to engage the projecting edge of the vamp in proximity to the knife and bend it inwardly so that it can pass between the cutting edge of the knives. The material operated upon by the trimming knives varies in thickness at the different portions of the shoe and accordingly in the preferred form of the invention the vamp bending device is mounted so that it can yield to accommodate variations in the thickness of the material operated upon. The vamp bending device is also preferably so constructed that it not only acts to bend the projecting edge of the vamp inwardly but also forces the bent in portion of the vamp in the direction of feed so that any liability is avoided of a fold in the blank being pressed in the opposite direction from the line of feed and being finally allowed to escape beneath the vamp bending device and the vamp trimming knife.

In the machine hereinafter described the vamp bending device above referred to projects beneath the plane in which the cutting edge of the vibrating trimming knife operates and thus acts as a guard to prevent the cutting edge of the knife from coming in contact with the tacks. The provision of a guard to prevent the cutting edge of the trimming knife from coming in contact with the lasting tacks is considered to be a feature of the present invention whether or not this guard also performs the further function of a vamp bending device.

In addition to the features of invention above referred to the machine hereinafter described embodies other features of invention hereinafter described and claimed the advantages of which will be obvious to those skilled in the art from the following description.

The present invention will be clearly understood from an inspection of the accompanying drawings in which

Figure 1 is a plan view of a machine embodying the same in the preferred form.

Fig. 2 is a view in side elevation of the machine illustrated in Fig. 1. Fig. 3 is a view in front elevation of the machine. Fig. 4 is a sectional view on a somewhat larger scale, looking from the front of the machine, said view being taken on a plane passing through the vertical shaft of the guiding roll. Fig. 5 is a sectional view looking from the side of the machine on a plane passing through the vertical shaft of the guiding roll, a portion of the frame of the machine being broken away to save space. Fig. 6 is a detail sectional plan view taken on a plane passing through the axis of the vibrating knife carrier. Fig. 7 is a detail plan view illustrating the construction and relative arrangement of the guiding roll, vibrating vamp trimming knife and vamp bending device, and Fig. 8 is a detail perspective view of the guide for the projection from the vibrating trimming knife.

The guiding roll which engages the lining and directs the vamp and lining between the cutting edges of the trimming knives is indicated at 1, and as shown, is arranged with its lower end directed downwardly so as to engage the sole of a shoe placed in the machine. The roll is secured to the lower end of a vertical shaft 2 by being screw-threaded thereon, the lower end of the shaft being provided with a screw-threaded portion and with a shoulder above the screw-threaded portion against which the upper end of the roll abuts. The upper surface of the roll is thus always brought to the same position whenever it is replaced in the machine after having been removed for the purpose of grinding its upper end. The roll is rotated constantly at a peripheral speed somewhat in excess of the speed at which the shoe is fed, and to enable the roll to exert an outward stretching action on the lining it is provided upon its peripheral surface with spiral ribs or corrugations as indicated in Figs. 2 and 3. The shaft 2 is mounted in bearings in the overhanging head of the machine frame and is rotated from the main driving shaft 3, journaled in the rear portion of the machine frame, by means of a belt 4 passing over a pulley 5 secured to the shaft 3 and a pulley 6 secured to the shaft 7, which shaft is provided with a worm 8 meshing with a worm wheel 9 secured to the shaft 2. The roll 1 as illustrated in the drawings, is preferably frusto-conical with its base of smaller diameter directed downwardly, the advantage of this shape of roll being that the lower end of the roll occupies less space in the shoe so that narrow toed shoes can be easily operated upon. The roll constitutes a gage to determine the distance from the sole at 125 which the vamp and lining are trimmed, and a further advantage of a roll having a frusto-conical shape is that the shoe may be tipped at certain portions of the shoe, if desired, without materially altering the distance of 130

the trimmed edges of the vamp and lining from the sole. The upper end of the guide roll constitutes one of the trimming knives, and in order that the end of the roll may be brought to the desired position with relation to the other trimming knife, the machine illustrated in the drawings is provided with means whereby the shaft 2 can be adjusted vertically. To this end the worm wheel 9 has a screw-threaded engagement with the shaft 2 and the wheel is locked rigidly to the shaft by means of a clamping bolt 10 passing through the hub of the wheel and provided with a recess to receive the shaft 2 as clearly indicated in Fig. 4. By loosening the clamping bolt 10, the worm wheel 9 is released from the shaft and the shaft can be rotated and thereby moved either up or down by reason of its screw-threaded engagement with the wheel. The wheel is held against longitudinal movement between the upper end of the bearing for the shaft 2 and an adjustable sleeve 11 having a screw-threaded engagement with the frame of the machine, as indicated in Figs. 4 and 5.

The trimming knife which coöperates with the upper end of the roll 1 to trim the vamp and lining is indicated at 12. The blade of this knife is curved in the arc of a circle and is secured by means of a clamp 13 and bolt 14 to a knife carrier 15. This carrier is pivotally mounted upon the frame of the machine by means of two pivot pins 16 and 17 which have a screw-threaded engagement with the machine frame and extend into bosses projecting from the carrier 15 on each side of the shaft 2. This construction is best illustrated in Fig. 6. The knife 12 is so arranged that its cutting edge moves across the upper end of the roll 1 toward and from the shaft 2, the center of the cutting edge, as best shown in Fig. 7, moving diametrically across the roll. During the operation of the machine a rapid vibrating movement is imparted to the knife carrier by means of an eccentric secured to the shaft 3 and an eccentric link and strap 18 connecting the eccentric and an arm projecting upwardly from the knife carrier. When the knife 12 is in its retracted position its cutting edge is separated from the roll 1, and in order to keep the cutting edge of the knife in proper position with relation to the upper end of the roll, the knife is provided with a forward projection 19 which passes across the upper end of the roll at one side of the shaft 2. To maintain the knife 12 accurately in its proper position during both its forward and retracting strokes, a guide is provided for the projection 19 of the knife. This guide is indicated at 20 and consists of a suitable guideway formed in a projection from a block 21, secured to the frame of the machine by means of a clamping screw 22 so as to be capable of vertical adjustment.

65 The vamp bending device which acts to

bend inwardly any outwardly projecting portions of the vamp and lining, is indicated at 23, and as shown, consists of a curved leaf spring provided at its free end with an upturned portion 24 and with a laterally extending portion 25, the portion 24 being so located as to engage the vamp before it reaches the knives and the portion 25 extending beneath the vibrating trimming knife. The other end of the spring 23 is bent downwardly and provided with a slot through which passes a clamping screw 26 by which the spring is secured to an oscillating carrier 27, the slot permitting a limited vertical adjustment of the spring to bring the vamp engaging portion into the desired position with relation to the knife. A rapid vibrating movement is imparted to the vamp bending device from an eccentric on the main shaft 3 by means of an eccentric strap and link 28 pivotally connected to an arm extending upwardly from the carrier 27. The pivot pin which connects the link 28 to the arm of the carrier 27 is adjustably secured in a slot in the link 28 so that the vamp bending device can be adjusted toward or from the guide roll to suit the thickness of material being operated upon. At each forward movement of the vamp bending device it engages the vamp and bends it inwardly so that it can pass between the cutting edges of the trimming knives. It will be noted from an inspection of Figs. 5 and 7 that the portion 24 of the vamp bending device is arranged at an angle to the path of motion of the bending device so that it acts not only to bend a portion of the vamp inwardly but to force the bent portion in the direction of feed and thereby prevent a fold of the vamp from escaping beneath the bending device and vibrating trimming knife. The eccentrics from which the vibrating trimming knife and bending device are actuated are secured to the shaft 3 at an angular distance apart 90° and are so arranged, as will be apparent from an inspection of Fig. 2, that the vamp bending device advances and engages the vamp and immediately thereafter and while the vamp is held by the vamp bending device the trimming knife advances and makes its cutting stroke. The vamp bending device thus acts not only to bend the vamp inwardly but also to hold the vamp in position while it is being trimmed. The vamp bending device engages the vamp at each forward movement and yields more or less according to the thickness of the materials.

By reason of the fact that the vamp bending device comprises a leaf spring it can be vibrated at a high rate of speed and still be caused to yieldingly engage the vamp at each actuation. The portion of the vamp bending device which extends beneath the blade of the vibrating trimming knife passes between the cutting edge of the knife and the

lasting tacks and thereby in addition to assisting the portion 24 in bending the vamp inwardly acts as a guard to prevent the cutting edge of the knife from coming in contact with the tacks.

The shoe is presented to the machine by the operator, the guide roll 1 extending inside of the vamp and lining with its lower end resting against the sole of a shoe. The 10 vibrating trimming knife and vamp bending device are operated at a high rate of speed and as the shoe is fed along by the operator, the vamp and lining are presented to the cutting edges of the knives by the roll and vamp bending device and the vamp and lining are trimmed at a distance from the sole determined by the height of the roll 1. The cutting edge of the vibrating knife moves in a plane substantially parallel to the plane of the shoe sole while severing the vamp and lining, but during the backward stroke of the 20 knife rises above the plane in which it cuts, on account of the fact that the knife carrier is mounted upon an axis above the roll 1 and substantially parallel to the direction of feed. There is, therefore, little, if any, liability of the edge of the knife coming in contact with the lasting tacks. Any such liability is, however, completely obviated by 25 the movement of the vamp bending device between the tacks and the cutting edge of the knife. It will be noted that the vamp bending device is mounted to move about an axis which is parallel to the axis of the knife 30 but which is more remote from the lower end of the guide roll 1. This arrangement of the vamp bending device permits it to act with greater certainty to engage outwardly extending portions of the vamp than it 35 would if it were mounted to move in substantially the same path as the edge of the trimming knife. This arrangement does not, however, bring the vamp bending device into such a position as to interfere with 40 the proper manipulation of the shoe or cause the bending device to strike the shoe below the line of lasting tacks. The shoe is fed by the operator to present the desired portions of the shoe to the action of the knives and 45 when the toe of the shoe is reached the shoe is swung about the roll 1 as a pivot.

It will be evident from an inspection of Fig. 7 that the swinging movement which is imparted to the shoe does not displace the 50 shoe with relation to the cutting edges of the trimming knives since the center of the cutting edge of the vibrating trimming knife moves in a path which passes through the axis of the roll. The shoe is guided principally by means of the guide roll 1, but the 55 vibrating bending device, by engaging the vamp near the edge of the shoe sole, also acts as a guide to limit the upward movement of the shoe and prevent the shoe from being 60 tipped so as to cause the vamp and lining

to be trimmed too close to the sole. On account of the rapidity with which the vamp bending device is actuated, no upward movement of the shoe is permitted during its backward movement and the device acts as a 70 guide in substantially the same manner as if it were stationary.

The invention having been thus described, what is claimed is:-

1. A vamp trimming machine, having, in combination, a trimming knife to trim the edge of the vamp of a lasted shoe, and a guard arranged to engage the lasting tacks and prevent the knife edge from coming in contact with the lasting tacks. 75

2. A vamp trimming machine, having in combination, a trimming knife for trimming the edge of the vamp and a guard located at one side of the plane in which the knife cuts to prevent the knife from coming in contact 80 with the lasting tacks. 85

3. A vamp trimming machine, having, in combination, a trimming knife to trim the edge of the vamp of a lasted shoe, and a yielding guard arranged to engage the lasting tacks and prevent the knife edge from 90 coming in contact with the tacks. 90

4. A vamp trimming machine, having, in combination, a trimming knife for trimming the edge of the vamp, a coöperating knife 95 arranged to extend inside of the vamp of a lasted shoe, and a vamp bending device extending in advance of the knives for bending the edge of the vamp inwardly toward the medial line of the shoe. 100

5. A vamp trimming machine, having, in combination, a trimming knife for trimming the edge of the vamp, a coöperating knife arranged to extend inside of the vamp of a lasted shoe, and a vibrating vamp bending 105 device for bending the edge of the vamp inwardly between the cutting edges of the knives. 110

6. A vamp trimming machine, having, in combination, a trimming knife for trimming the edge of the vamp and means for bending the edge of the vamp inwardly toward the medial line of the shoe into position to be acted upon by the trimming knife. 110

7. A vamp trimming machine, having, in combination, a trimming knife to trim the edge of the vamp and a vibrating vamp bending device to bend the edge of the vamp inwardly toward the medial line of the shoe into a position to be acted upon by the trimming knife. 115 120

8. A vamp trimming machine, having, in combination, a trimming knife to trim the edge of the vamp and a vibrating vamp bending device acting to bend the vamp inwardly toward the medial line of the shoe and arranged to yield when brought into engagement with the vamp. 125

9. A vamp trimming machine, having, in combination, vamp trimming knives, and 130

means acting on the shoe lining in proximity to the trimming knives to stretch the lining transversely to the direction of feed.

10. A vamp trimming machine, having, in combination, vamp trimming knives, and a rotating roll provided with spiral ribs upon its peripheral surface arranged to engage the lining in proximity to the trimming knives and exert an outward wiping action thereon.

11. A vamp trimming machine, having, in combination, vamp trimming knives, and a frusto-conical guiding roll arranged to act upon the vamp and lining in proximity to the trimming knives and direct the vamp and lining between the cutting edges of the knives.

12. A vamp trimming machine, having, in combination, vamp trimming knives, a frusto-conical guiding roll arranged to act on the vamp and lining in proximity to the knives and direct the vamp and lining between the cutting edges of the knives, and means for rotating the roll.

13. A vamp trimming machine, having, in combination, vamp trimming knives, a frusto-conical roll provided upon its peripheral surface with spiral ribs arranged to exert an outward wiping action on the shoe lining in proximity to the trimming knives, and means for rotating the roll.

14. A vamp trimming machine, having, in combination, a guide roll for the vamp and lining having one end directed toward the sole of a shoe placed in the machine, a vibrating trimming knife working across the other end of the roll, a knife coöperating with said vibrating knife to trim the vamp and lining, and means for rotating the roll.

15. A vamp trimming machine, having, in combination, a guiding roll for the vamp and lining, a vibrating trimming knife working across the end of the guiding roll, and a knife on the end of the guiding roll coöperating with the vibrating knife to trim the vamp and lining.

16. A vamp trimming machine, having, in combination, a guiding roll for the vamp and lining having one end directed toward the sole of a shoe placed in the machine, a vibrating trimming knife working across the other end of the roll and a knife on the guiding roll coöperating with the vibrating knife to trim the vamp and lining, and means for rotating the roll.

17. A vamp trimming machine, having, in combination, a guiding roll for the vamp and lining having one end directed toward the sole of a shoe placed in the machine and being constructed to stretch the lining transversely to the direction of feed, a trimming knife working across the other end of the roll, a knife coöperating with said trimming knife to trim the vamp and lining and means for rotating the roll.

18. A vamp trimming machine, having, in

combination, a guide roll for the vamp and lining having one end directed toward the sole of a shoe placed in the machine and being provided upon its peripheral surface with spiral ribs arranged to exert an outward wiping action on the lining, a trimming knife working across the other end of the roll and a knife coöperating with said trimming knife to trim the vamp and lining, and means for rotating the roll.

70

75

19. A vamp trimming machine, having, in combination, a vibrating trimming knife mounted to move about an axis substantially parallel to the direction in which the work is fed to the knife and a knife coöperating with said vibrating knife to sever the vamp and lining.

20. A vamp trimming machine, having, in combination, a guide roll for the vamp and lining having one end directed toward the sole of a shoe placed in the machine, a vibrating trimming knife mounted to move about an axis substantially parallel to the direction in which the work is fed to the knife, a knife on the guiding roll coöperating with the vibrating knife to trim the vamp and lining, and means for rotating the roll.

21. A vamp trimming machine, having, in combination, a guiding roll for the vamp and lining having one end directed toward the sole of a shoe placed in the machine, a vibrating trimming knife working across the other end of the roll provided with a projection extending beyond the cutting edge of the knife, a knife on the roll coöperating with the vibrating knife to trim the vamp and lining, means for rotating the roll, and a guide for the projection on the vibrating knife.

22. A vamp trimming machine, having, in combination, a guiding roll for the vamp and lining having one end directed toward the sole of a shoe placed in the machine, a vibrating trimming knife mounted to move about an axis substantially parallel to the direction in which the work is fed to the knife and provided with a projection extending beyond the cutting edge of the knife, a knife on the roll coöperating with the vibrating knife to trim the vamp and lining, means for rotating the roll, and a guide for the projection on the vibrating knife.

23. A vamp trimming machine, having, in combination, a guiding roll for the vamp and lining having one end directed toward the sole of a shoe placed in the machine, a trimming knife working across the other end of the roll, a knife on the guiding roll coöperating with the trimming knife to trim the vamp and lining, a shaft to which the roll is secured, a gear having a screw-threaded engagement with the shaft, and a clamping device for clamping the gear to the shaft, whereby the shaft can be released from the gear and rotated to adjust the guiding roll.

24. A vamp trimming machine, having, in

90

95

100

105

110

115

120

125

130

combination, a guide roll for the vamp and lining having one end directed toward the sole of a shoe placed in the machine, a trimming knife working across the other end of the roll, a knife coöperating with said trimming knife to trim the vamp and lining; and means for rotating the roll.

25. A vamp trimming machine, having, in combination, a vibrating trimming knife, a knife coöperating therewith to trim the vamp and lining, a guide arranged to bear on the shoe inside of the vamp and lining and raise the vamp and lining and direct them between the cutting edges of the knives and a guide 10 extending below the plane in which the trimming knife cuts to bear against the vamp near the edge of the shoe sole and coöperate with the first mentioned guide to determine the distance of the cut from the sole.

20 26. A vamp trimming machine, having, in combination, vamp trimming knives, and a vibrating vamp bending device and guide arranged to engage the projecting edge of the vamp and bend it inwardly and provided 25 with a portion extending below the plane in which the trimming knives cut to engage the vamp near the edge of the shoe sole.

27. A vamp trimming machine, having, in combination, vamp trimming knives, and a frusto-conical guide roll arranged to direct the vamp and lining between the cutting edges of the knives and having its base of smaller diameter directed toward the sole of a shoe placed in the machine.

30 28. A vamp trimming machine, having, in combination, a frusto-conical guide roll for the vamp and lining having its base of smaller diameter directed toward the sole of a shoe placed in the machine, a vibrating trimming knife working across the other end of the roll, and a knife coöperating with said vibrating knife to trim the vamp and lining.

29. A vamp trimming machine, having, in combination, a frusto-conical guide roll for the vamp and lining having its base of smaller diameter directed toward the sole of a shoe placed in the machine, and being provided upon its peripheral surface with spiral ribs arranged to exert an outward wiping 45 action on the lining, a trimming knife working across the other end of the roll, a knife coöperating with said trimming knife to trim the vamp and lining, and means for rotating the roll.

50 30. A vamp trimming machine, having, in combination, vamp trimming knives, and means acting on the projecting edge of the vamp of a lasted shoe in proximity to the knives to bend the vamp inwardly and force 55 the bent-in portion relatively to the shoe in the direction of feed.

31. A vamp trimming machine, having, in combination, vamp trimming knives, and a vibrating vamp bending device constructed 60 to bend a portion of the vamp inwardly in

proximity to the knives and force the bent-in portion in the direction of feed.

32. A vamp trimming machine, having, in combination, a trimming knife arranged to extend inside of the vamp of a lasted shoe, a 70 vibrating trimming knife coöperating therewith to trim the projecting edges of the vamp and lining of the shoe, a vibrating vamp bending device arranged to engage the vamp and bend it inwardly toward the medial 75 line of the shoe, and means for actuating the vamp bending device to cause it to engage the vamp in advance of the vibrating knife and remain in engagement with the vamp during the cutting action of the knife. 80

33. A vamp trimming machine, having, in combination, vamp trimming knives arranged to trim the projecting edges of the vamp and lining of a lasted shoe, and a vibrating bending device arranged to engage 85 the vamp and bend it inwardly toward the medial line of the shoe, said device including a leaf spring arranged to yield when the bending device engages the vamp.

34. A vamp trimming machine, having, in combination, a trimming knife arranged to extend inside of the vamp of a lasted shoe, a vibrating trimming knife coöperating therewith to trim the projecting edges of the vamp and lining of the shoe, and mounted to move 90 about an axis substantially parallel to the direction in which the work is fed, and a vibrating vamp bending device mounted to move about an axis parallel to that of the vibrating knife and having its working face arranged to move in an arc of greater radius 95 than the arc traversed by the cutting edge of the vibrating knife. 100

35. A vamp trimming machine, having, in combination, vamp trimming knives arranged to trim the projecting edges of the vamp and lining of a lasted shoe, a pivotally mounted carrier, a leaf spring secured to the carrier provided at its free end with a surface to engage the vamp and bend it inwardly 105 toward the medial line of the shoe, and means for oscillating the carrier. 110

36. A vamp trimming machine, having, in combination, a trimming knife arranged to extend inside of the vamp of a lasted shoe, a 115 vibrating trimming knife coöperating therewith to trim the projecting edges of the vamp and lining of the shoe, and a vibrating vamp bending device to bend the vamp inwardly toward the medial line of the shoe provided 120 with a portion extending beneath the vibrating knife.

37. A vamp trimming machine having, in combination, a vibrating trimming knife, a coöperating knife arranged to extend inside 125 of the vamp and lining of a lasted shoe, a guide arranged to bear on the shoe inside of the vamp and lining and raise the vamp and lining and direct them between the cutting edges of the knives, and means for bending

the edge of the vamp inwardly toward the medial line of the shoe in position to be acted upon by the knives.

38. A vamp trimming machine, having, in combination, a trimming knife for trimming the edge of the vamp and means for presenting the edge of the vamp to the trimming knife comprising a guide arranged to bear on the shoe inside of the vamp and lining and 10 raise the vamp and lining and a vibrating bending device acting to engage the edge of the vamp and bend it inwardly toward the medial line of the shoe.

39. A vamp trimming machine, having, in

combination, a vibrating trimming knife 15 mounted to move about an axis substantially parallel to the direction in which the work is fed to the knife, and a knife arranged to extend inside of the vamp and lining of a lasted shoe and coöperate with the vibrating 20 trimming knife to sever the vamp and lining.

In testimony whereof I affix my signature, in presence of two witnesses.

JOHN B. HADAWAY.
